HERMANN RAPPOLD, OF DUREN, GERMANY, ASSIGNOR TO ZIMMERMANN & JANSEN, GESELLSCHAFT MIT BESCHRANKTER HAFTUNG, OF DUREN, RHEINLAND, GERMANY.

MEANS OF WORKING BLAST HEATERS USED IN CONNECTION WITH BLAST FURNACES.

Application filed April 6, 1925, Serial No. 732, and in Germany May 22, 1924.

The blast to be blown into blast furnaces is heated to a rather high temperature for saving fuel. For this purpose, generally, a series of apparatus is used for one blast furnace, in such a way that part of said apparatus is heated by internal combustion of gas to a high temperature while the other part delivers its own heat absorbed during the preceding working (heating) period to 5 the blast blown-in and thus heats the latter.

Thus, with each single apparatus it is the question of two separate working periods, namely the heating period (hereinafter briefly called: "gas") and the blowing period 15 (hereinafter briefly called "blast").

For the reversal of one apparatus from "gas" to "blast," or vice versa, a plurality of shut-off devices are provided and adapted to control the heating gas, the combustion air, 20 the cold blast, the hot blast, and so on.

The hitherto known method of working the blast heaters suffers from the drawback that by an incorrect attendance to the shut-off devices a faulty connection is possible 25

which results in a considerable danger for the whole plant and for the attending persons. For instance, the gas and cold blast could be simultaneously connected with one apparatus whereby explosions might occur.

30 Furthermore, the gas could be opened and the combustion air shut off in which case the gas cannot be ignited owing to lack of air and fills the apparatus so that at the admission of air explosions would take place in 35 the apparatus and in the flue. Other faulty connections are possible which however need not be further described.

The present invention relates to an improved means of working blast heaters, by 40 which faulty connections are made impossible, said means consisting essentially in operating the shut-off devices of one apparatus, by positively interconnecting the same, always in their correct succession only 45 required for a proper working of the heater.

Supposing that the shut-off devices be designated by: 1, 2, 3, 4, 5 and operated in the written succession for reversing from "gas" to "blast," consequently, the positive inter- 50 connection of the single shut-off devices results, when reversing vice versa from "blast" to "gas," in the operation of the shut-off

devices taking place in reverse direction from 5 to 1.

The manner in which the positive interconnection of the shut-off devices is attained is immaterial as long as, when building the 55 plant, the correct succession in one direction of connection required for working the blast heater, is maintained, the correct succession in the other direction of connection resulting therefrom per se.

60 The energy required for reversing the series of shut-off devices may be derived from any appropriate source: either hand power, or mechanical power, or electrical power, or hydraulic or pneumatic (compressed-air) 65 power, being possible; and, if desired, said power source can be applied from any distant place or places.

The accompanying drawings illustrate in 70 Figs. 1 and 2 diagrams of a preferred arrangement for putting the invention into practice, in two different positions of its parts, the power employed in connection therewith being a pressure-medium, such as compressed-air or pressure-water.

75 The arrangement comprises five shut-off devices, namely: for gas admission 1, supply of combustion-air 2, waste-gas exhaust 3, cold-blast admission 4, hot-blast escape 5.

The operating means comprise four two-plunger cylinders 1^a, 2^a, 3^a, 4^a, each located intermediate two adjacent shut-off devices, while a four-way cock 6 serves as main operating contrivance, which can also be replaced by an operating cylinder similar to 80 those 1^a—4^a.

85 All said operating means can be simultaneously reversed by a lever system α attached to the plunger-rods of the two-plunger cylinders and to the four-way cock respectively.

90 The operating means comprise further five one-plunger cylinders 1^b, 2^b, 3^b, 4^b, 5^b, of which each one is directly connected by its plunger-rod with the movable shut-off member of one shut-off device.

95 All the cylinders are in communication with each other and with the four-way cock by means of a pipe system for the pressure-medium in a manner hereinafter described.

100 Supposing that the operating means are in the position illustrated in Fig. 1, the pressure-medium arriving at α flows in the di-

rection of arrows first through the four-way cock b and the pipe 1^e to the one-plunger cylinder 1^a where it forces the plunger 1^e outwards until it arrives at its dotted end 5 position, thereby closing the shut-off device 1. This being completed, the plunger 1^a liberates the path to the pipe 1^f for the pressure-medium. The latter flows through the pipe 1^f , the rear chamber of the two-plunger cylinder 1^a and the pipe 2^g to the one-plunger cylinder 2^d of the shut-off device 2. There, the plunger 2^e is pressed outwards into its dotted end position and, while closing the shut-off device 2, liberates the path for the 10 pressure-medium to the pipe 2^f , the rear chamber of the two two-plunger cylinders 2^a , the pipe 3^g and the one-plunger cylinder 3^d , where the same proceeding takes place as in the two first one-plunger cylinders. In a 15 similar way, the successive operation of the following shut-off devices 4 and 5 takes place, the direction of movement of the latter being however opposite to that of the three first shut-off devices, that means, the devices 20 4 and 5 are successively opened after the device 3 is closed, this depending upon the working conditions of the heater. Upon the device 5 being opened, the total operation in one direction is finished.

30 The exhaust of the pressure-medium of each single one-plunger cylinder 1^a — 5^a flows during the operation through the pipes 1^h , 2^h , 3^h , 4^h , 5^h and through the middle chambers of the two-plunger cylinders 1^a — 4^a (see 35 outer connection-pipe k of same) and the four-way cock b respectively into the open air.

The dot-and-dash line pipes 1^i , 2^i , 3^i , 4^i are not used for the above-described operation, the same leading therefore from the one-plunger cylinders into the neutral closed fore chambers of the two-plunger cylinders.

40 As shown in Fig. 2, by reversing the lever system z , the operation takes place in reverse succession, namely: shutting-off first hot-blast (at 5), then cold-blast (at 4), and opening first waste-gas (at 3), then combustion-air (at 2), and finally gas (at 1).

45 The position of the operating means as well as the direction of arrows shows that the pressure-medium arriving at z flows through the four-way cock b and pipe 5^h to the one-plunger cylinder 5^a and forces the plunger 5^e into the dotted end position 50 thereby closing the shut-off device 5. This operation being completed, the path is free for the pressure-medium to flow through pipe 4^i (not used in the former operation afore-described), the fore chamber of the two-plunger cylinder 4^a and pipe 4^h to the one-plunger cylinder 4^a , where the same proceeding takes place as at 5^a . In a similar way, the pressure-medium flows each 55 time after completed operation of one shut-off device to the one-plunger cylinder of the

next following shut-off device, until finally shut-off device 1 is opened.

In this case, the exhaust of the pressure-medium from the one-plunger cylinders flows through the pipes 5^g — 1^g and through 70 the middle chambers of the two-plunger cylinders 4^a — 1^a (see outer connection-pipe k of same) and the four-way cock b respectively into the open air.

In this case, further, the dot-and-dash line 75 pipes 4^i — 1^i (like 1^i — 4^i in the former case) are not used, the same leading therefore from the one-plunger cylinders into the (now neutral) closed rear chambers of the two-plunger cylinders.

80 If the working conditions of the blast heater should require any other succession of operation of the single shut-off devices, this can of course be executed by a synonymous change of the pipe connections.

85 An additional particular contrivance is provided in connection with the shut-off device 4, which is to open but slowly, to suit the working conditions of the blast heater. For this purpose, in the pipe 4^h , which when opening the shut-off device 4 serves as outlet pipe (Fig. 1), a throttling member l is inserted and adapted to throttle the cross-section of said outlet pipe in such a way 90 that the pressure-medium can escape and thus the plunger 4^e can advance but slowly. As, however, the same pipe 4^h serves in Fig. 2 also as admission pipe for the pressure-medium, a bye-conduit with a non-return valve m therein is placed around the throttling member l . Said non-return valve permits of the pressure-medium flowing around the throttling member l if the pipe 4^h serves as admission pipe (Fig. 2) whereas it 95 compels the same to flow through the throttling member l if the pipe 4^h serves as outlet pipe (Fig. 1).

100 What I claim, is:

1. An arrangement for automatically and positively operating the shut-off devices of 110 blast heaters for blast furnaces by a pressure-medium always in their correct succession only required for a proper working of the heater: comprising, in combination with said shut-off devices, a series of two-plunger cylinders, each one located intermediate two adjacent shut-off devices, a main operating contrivance, a lever system in connection with said cylinders and with said main operating contrivance and adapted to simultaneously reverse the operative position of the same, a series of one-plunger cylinders, each one connected by its plunger-rod directly with one shut-off device, and a pipe system for the pressure-medium so connected with all said cylinders and with said main operating contrivance that only at the completion of the operation of one shut-off device the next following one is operated, and 115 so on.

2. In an arrangement as specified in claim 1: means for opening one of said shut-off devices but slowly.
3. In an arrangement as specified in claim 5 1: a throttling member located in said pipe system and adapted to permit the opening of said shut-off devices but slowly.
4. In an arrangement as specified in claim 1: a throttling member located in said pipe

system and adapted to permit the opening 10 of said shut-off devices but slowly, a bye-conduit placed around said throttling member, and a non-return valve in said bye-conduit.

In testimony whereof I have hereunto set 15 my hand.

HERMANN RAPPOLD.
